FASTENING MEANS FOR CARTONS OR THE
LIKE

Edith R. Witherspoon, Englewood, N. J.

Application November 13, 1936, Serial No. 110,573

1 Claim. (Cl. 206—1.5)

This invention relates to refillable containers, cartons and the like and particularly to a novel fastening means therefor.

One object of the invention is a novel fastening means which may be employed for refillable shaving sticks, lipsticks, eyebrow pencils, for canisters, etc.

Further objects of the invention will herein-after appear.

For a better understanding of the invention reference may be had to the accompanying drawing forming a part of this application wherein:

Fig. 1 is a view illustrating a canister can or canister carton embodying the invention;

Fig. 2 is a view illustrating a refillable shaving stick holder embodying another form of the invention.

In Fig. 1 I have indicated my invention as applied to a canister can or carton wherein a tongue 1 is shown as mounted on the interior of a closing cap or lid 30 and following the interior curvature thereof in a circumferential direction. The body of the can 31 is provided with a cooperating fastening tongue 12 which is fastened to the exterior surface thereof near the upper edge and extends vertically downward. The tongue 1 is tapered in width, as indicated, and is curved to have on one side a convex edge 8 and on its other side a concave edge 9. In the particular embodiment shown, the tongue 1 is formed integrally with a main body part 1' which is secured in any suitable manner flush against the interior cylindrical wall of the lid 30. This body part 1' may be soldered, welded or otherwise fastened to the lid 30 or it may be provided with an integral fastening clip 10 which is passed through a slot formed in the wall of the lid 30 and bent over the edge of the slot to contact the outer surface of the wall.

The tongue 12 extends downwardly from a main body part 13 lying flush against the outer cylindrical wall of the can 31 and soldered or otherwise fastened thereto. The body part 13 may, if desired, also be fastened to the can 31 by means of an integrally formed clip 14 which is passed inwardly through a slot formed in the wall of the can 31 and then extended upwardly along the inner surface of the wall to and over the upper edge of the can when it then passes downwardly flush along the outer surface of the wall of the can.

With the above described construction the lid 30 may be readily put in position over the can 31.

and the two readily fastened together by relatively rotating the lid and can to bring the tongue 1 underneath the tongue 12, the curvature and shape of the tongue 1 contributing to the facility with which the fastening and unfastening may be effected. Practice has demonstrated that the particular shape of the tongue 1 with the convex and concave sides contributes toward and facilitates the interlocking and disengagement operations.

In Fig. 2 I have shown an embodiment of my invention wherein a refillable holder 35 is shown for receiving shaving stick refills, lipstick refills, eyebrow pencil refills and the like. The holder 35 is provided with a tongue 12 similar to the tongue 12 of Fig. 1. It is fastened to the interior of the holder 35 and extends vertically downward. The refill 36 is provided near the lower end thereof with a fastening tongue similar to the tongue 1 of Fig. 1. In this case, however, it is fastened to the outside of the base 36 of the refill and follows the circumferential contour thereof. To insert the refill having the base 36, it is only necessary to insert it within the holder 35 and to impart relative rotary movement to the holder 35 and the base 36 to cause the tongue 1 to pass beneath the tongue 12; and, similarly, to remove the refill or the base of the refill, it is only necessary to impart relative rotary movement in the opposite direction to release the tongue 1 from underneath the tongue 12 whereby the two parts may be separated by longitudinal relative movements.

Preferably in each embodiment of the invention tongue 12 at the tip end thereof is bent in a direction away from the adjacent supporting wall to facilitate engagement of the tongues during the fastening operation.

The fastening tongues 1 and 12 are preferably formed of thin metal and where the devices themselves are made of thin metal these tongues may be formed integrally with the same and, as above indicated, when the tongues are not formed integrally with the devices they may be fastened in operative position in any suitable manner, as for example by soldering, welding, or the like.

Certain features of the invention are applicable to other uses than those specifically disclosed in the drawing, such for example as removable telephone number plates, removable sanitary mouth pieces for telephones, telephone switchboard plugs, and electric bulb and socket connections. In the latter use the tongue 1 could

be formed on the exterior of the bulb base, while the tongue 12 is fastened to the interior of the socket shell, and multiple wall plugs may be formed in a single unit, including a number of such sockets whereby a multiplicity of lamp bulbs may be readily connected to a single outlet in a simple and satisfactory manner. Other uses of the invention or certain features of it will be obvious and it is deemed unnecessary to describe all such uses.

I claim:

A device of the character described comprising a cylindrical type of can or container element, a closure having a depending skirt to telescope and surround the upper part of the side wall of said element, said skirt and side wall portion being closely spaced and presenting opposed surfaces in the assembled relation of said element and closure, and two fastening members, each of said members being of thin sheet metal and having a base portion and a relatively narrow and flexible tongue, the base portion of one of said members being mounted on and lying flat against one of said surfaces, the base portion of the other of said members being mounted on and lying flat against the other of said surfaces, each

of said members throughout its length conforming substantially to the curving contour of the surface on which the member is mounted, the member mounted on said element having the base portion thereof adjacent the upper edge of said element and having the tongue thereof extending downwardly, the member mounted on said closure skirt extending substantially circumferentially thereof, the tip of one of said tongues being slightly spaced from the surface on which the corresponding base portion is mounted, whereby said tongues in the assembled relation of said element and closure are closely confined between said surfaces, have interlocking interengagement and extend substantially at right angles to each other to provide for disengagement and engagement by relative rotation of said element and closure, the tongue mounted on said closure skirt being tapered to its tip end and on its upper edge being concavely shaped and on its lower edge being convexly shaped, whereby the shape of said last named tongue facilitates its engagement and holding action with the other of said tongues.
